FEED STRIP LOCATOR

Walter Sorensen, Moline, Ill.

Application July 17, 1945, Serial No. 605,615

20 Claims. (Cl. 59—6)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to dies for making ammunition belt links. More specifically it relates to an improvement on such dies designed to render more nearly perfect the links produced thereby.

In the art of manufacturing cartridge or ammunition belt links the link is ordinarily formed from sheet metal and comprises a pair of axially aligned, spaced apart loops of generally annular shape adapted to receive and grip a cartridge, one of said loops being conformed to the neck and/or shoulder of a cartridge, together with a third loop offset from the said coaxial loops but connected thereto and having its axis generally parallel to the axis of said coaxial loops. The construction is such that the offset loop is in alignment with the space between the said coaxial loops and is of a breadth slightly less than the distance between said coaxial loops whereby a plurality of such loops may be articulated to form a disintegrating belt by placing the offset loop of each link between the coaxial loops of an adjacent link and passing cartridges respectively into the series of three loops thus aligned. The diameter of the offset loop is slightly greater than the portion of the cartridge which it receives whereby it is adapted to rotate about said cartridge, while the coaxial loops firmly grip the cartridge and hold it in place in the belt.

It has been the practice to form such belt links by the use of suitable dies adapted to cut and form the links from a strip of sheet metal fed continuously through said dies. In most instances the arrangement has been such that the strip of metal fed into the dies is of a width adequate for the making of a single link only.

The dies normally comprise an upper and a lower die, the former being movable and said dies being adapted to form the links by acting, in a plurality of successive operations, upon each individual area or segment of the strip. On one die assembly widely accepted for this purpose spaced apart, aligned cuts are made in one operation and said cuts are completed or merged in a succeeding operation. Although means have been provided for so directing the progress of the strip through the dies that the said spaced apart, aligned cuts are intended to be in perfect alignment with the cutting member which completes and merges said cuts at the time of such completion, the said means have not been en-

2

tirely effective for this purpose, for the reason that slivers are frequently formed on the links making them imperfect and also resulting in undue wear upon the die parts with which they come in contact in succeeding operations.

It is an important object of this invention to provide means for maintaining more nearly perfect alignment of the strip material in a cartridge belt link die assembly.

10 Another object of this invention is to provide an alignment assembly which may be installed in used belt link dies for improving their ability to maintain the material strip in proper alignment.

15 A still further object of my invention is to provide novel construction in a belt link die strip aligning means.

In general my invention in its preferred form comprises a base supporting a tang or lug of 20 predetermined size adapted to successively engage at least one of the preferably parallel sides of each of succeeding openings, one of which is formed in the feed strip in the initial operation in the formation of each link.

25 It will of course be apparent that my invention may be either a detachable or permanent fixture in a die assembly and that it may be used either in conjunction with other aligning means or alone.

30 In order that a clear and concise disclosure of my invention may be made, I have accompanied this specification with suitable drawings illustrating my invention wherein:

Fig. 1 is a fragmentary plan view of a top die 35 of a die assembly, a part of a feed strip being shown in place thereon which has cuts defining a few successive stages of embryo links and the assembly being shown in inverted position;

Fig. 2 is a fragmentary longitudinal section 40 through a die assembly incorporating my invention;

Fig. 3 is a perspective view of one of the elements comprising my invention in its preferred form said element being shown inverted from its 45 preferred operative position;

Fig. 4 is a perspective view of another element included in the preferred form of my invention, the same being similarly inverted; and

Fig. 5 is a top plan view of a fragment of a feed strip having cuts defining various stages of 50 embryo links.

Referring now to the drawing in greater detail, the numeral 30 designates the top die of the die assembly shown fragmentarily, and 31 designates the lower die of this assembly. In the par-

ticular die assembly illustrated in part, seven stages are provided, the more progressed ones of which are not shown in the drawing. It will be understood that as the top die comes down upon the feed strip supported on the lower die the seventh die station completes the formation of a link and the first die station forms the initial general outline of an embryo link. Intervening die stations perform operations upon intervening embryo links directed toward bringing those embryo links upon which they are respectively operating more nearly into the condition of finished links, said latter stations being progressively arranged from two to six with reference to the degree of completion of the respective embryo links.

When a feed strip is started through such a die assembly, it is introduced to the first die station whereupon there are formed in its end cuts such as those shown in the area designated by the letter A in Fig. 5. These cuts include cuts 1, 2, 3, 2a, and 3a. It will be noted that the plurality of cuts designated by numeral 1 define a complete cutout or an opening, the generally parallel sides of which are substantially in alignment with the inner ends of the cuts 2a and 3a. When the area A has moved over into the position designated by B, it is acted upon by die elements adapted to sever the material between the cut 2a and the aligned one of the parallel sides of cut 1 and the material between the cut 3a and the one of the parallel segments of the cut 1 which is aligned therewith. For purposes of clarification it may be mentioned that a portion of the starting end of each strip is wasted due to the fact that the last half of an embryo link together with the first half of a succeeding embryo link is formed therein, the said last half of the first said embryo link being without a first half; however, all succeeding links are full and the operation is the same for succeeding links as for the initial one. Thus it will be seen that as the top die comes down upon the metal strip supported upon the lower die, station No. 1 partially forms a pair of generally parallel fingers or tongues which are in approximate registration with one another while station No. 2 completes the formation of an attached, oppositely directed but parallel tongue and also completes the formation of the registering parallel tongues of the preceding embryo link.

It is at station No. 2 that considerable difficulty has been experienced in the past with the formation of slivers on the feed strip, it having been heretofore impossible to maintain the strip in a position such that the inner ends of cuts 2a and 3a together with respectively aligned sides of cut 1 are in perfectly parallel and aligned relationships to the cutting or stamping member operating at station No. 2 to merge said cuts 2a and 3a with cut 1. It is to insure such alignment and the elimination of slivers at this point, that I have directed my invention, a preferred form of which as herein disclosed includes a holder member designated generally by the numeral 10 and having an enlarged or deep section 12 together with oppositely directed ears 11. In the enlarged section 12 a cutout 13 is provided having adjacent its top expanded sections 14 and 15. Into the cutout 13 I fit a locating member designated generally by the numeral 18 and having a tang or lug 19 adapted to be partially received in the smaller dimension portion of the cutout 13, together with ears 21 and 22 which, when in operation, are received in the enlarged

sections 14 and 15 of the cutout 13. It will be noted that the tang 19 is of a length appreciably greater than that of the reduced portion of the cutout 13 so that when in place therein, its free end extends substantially beyond the member 10. On the other hand the width of the tang 19 is substantially less than that of the reduced section of the cutout or slot 13 and tapped holes or bores 32 and 33 are provided in the enlarged section 12 extending from the opposed ends thereof to the restricted portion of the cutout 13. Setscrews 25 threaded in the tapped bores 32 and 33 enable the fixing of the tang 19 at any lateral position in the cutout 13 permitted by the difference between its transverse dimension and that of the said cutout 13.

As will be apparent from Figs. 1 and 2, the part 10 is mounted on the bottom portion of the top die by suitable fastening means 27 in a position such that parts 12 and 19 project downwardly. When the top die is in lowered position the lower end of the tang 19 is received in a cutout 34 provided in the lower die 31. Fig. 1 illustrates clearly that the width of the tang 19 is substantially equal to the distance between the parallel sides of the cut 1 and that said tang fits within negligible tolerances between said parallel sides when the top die is brought down into operative relation to the feed strip. Such being the case and it being remembered that the position of the member 18 may be adjusted in the cutout 13 by the setscrews 25 to compensate for any discrepancies and/or for wear of the tang 19, it will be apparent that the lateral position of the feed strip at station No. 2 may be accurately regulated so that said parallel segments of the cut 1 together with the inner ends of the cuts 2a and 3a are in perfect alignment with the cutting element or cutting elements which operate to merge said cuts in the manner heretofore described, thus avoiding the formation of slivers.

It will be noted that the corners on the extended end of the tang 19 are rounded; such construction insures that the tang will enter the space between the parallel sides of the cut 1, said rounded corners enabling the tang 19 to shift the feed strip laterally, if necessary, in order to gain such entrance. Such shifting will have the effect of placing the cuts 2a and 3a and the parallel sides of the cut 1 in the perfectly aligned position desired.

The openings 7 in the feed strip cooperating with sharpened prongs 35 have heretofore been relied upon for insuring the desired alignment of the cuts and, as indicated, have not generally proved to be adequate for the purpose intended. My improved alignment means may be employed either in cooperation with the openings 7 and prongs 35 or may be relied upon as the sole aligning means.

Although I have described a specific embodiment of my invention for illustrative purposes, it will be understood that various modifications, alterations, and substitutions may be made therein by one skilled in the art without departing from the true spirit and scope of my invention as defined in the appended claims.

I claim:

1. A feed-strip aligning means for ammunition belt-link dies comprising, a holding member including means forming a cutout extending from its top to its bottom, said cutout being enlarged in its top portion, a locator element received in said cutout and projecting beyond the bottom of

said holding member, the fit of said locator element in said cutout being loose in at least one direction, a head on said locator loosely receivable in said enlarged portion of said cutout, and means for adjustably fixing the position of said locator in said cutout.

2. A feed-strip aligning means for ammunition belt-link dies comprising, a holding member including means forming a cutout extending from one of its surfaces to a generally opposite surface, said cutout being enlarged adjacent said first surface, a locator element received in said cutout and projecting beyond said second surface of said holding member, the fit of said locator element in said cutout being loose in at least one direction, a head on said locator loosely receivable in said enlarged portion of said cutout, and means for adjustably fixing the position of said locator in said cutout.

3. A feed-strip aligning means for ammunition belt-link dies comprising, a holding member including means forming a cutout extending from one of its surfaces to a generally opposite surface, said cutout being enlarged adjacent said first surface, support means on said holding member for supporting said member in a die or the like, a locator element received in said cutout and projecting beyond said second surface of said holding member, the fit of said locator element in said cutout being loose in at least one direction, a head on said locator loosely receivable in said enlarged portion of said cutout, and means for adjustably fixing the position of said locator in said cutout.

4. A feed-strip aligning means for ammunition belt-link dies comprising, a holding member including means forming a cutout extending from one of its surfaces to a generally opposite surface, said cutout being enlarged adjacent said first surface, a locator element received in said cutout and projecting beyond said second surface of said holding member, and a head on said locator adapted to be received in the said enlarged portion of the cutout.

5. A feed-strip aligning means for ammunition belt-link dies comprising, a holding member, a locator element movably mounted on said holding member and projecting therefrom, and means for adjustably fixing the position of said locator element on said holding member.

6. A feed-strip aligning means for ammunition belt-link dies comprising, a holding member including means forming a cutout extending from one of its surfaces to a generally opposite surface, a locator element adapted to be received in said cutout and to project beyond the said holding member in at least one direction, the fit of said locator element in said cutout being loose in at least one direction, and means for adjustably fixing the position of said locator in said cutout.

7. A feed-strip aligning means for ammunition belt-link dies comprising, a holding member including means forming a cutout extending from one of its surfaces to a generally opposite surface, said cutout being enlarged adjacent said first surface, a locator element received in said cutout and projecting beyond the said second surface of said holding member, a head on said locator receivable in the said enlarged portion of the cutout, and means for adjusting the position of said locator relative to an independently fixed point.

8. A feed-strip aligning means for ammunition belt-link dies comprising a holding member, a

locator element projecting from said holding member, and means for adjusting the position of said locator element relative to an independently fixed point.

5. 9. A feed-strip aligning means for ammunition belt-link dies comprising, a holding member including means forming a cutout, a locator element adapted to be received in said cutout and to project beyond a surface of said holding member, the fit of said locator element in said cutout being loose in at least one direction, and means for adjustably fixing the position of said locator in said cutout.

10. 10. A feed-strip aligning means for ammunition belt-link dies comprising, a holding member including means forming a cutout, a locator element adapted to be received in said cutout and to project beyond a surface of said holding member, and means for adjusting the position of said locator in said cutout.

15. 11. A feed-strip aligning means for ammunition belt-link dies comprising, a holding member including means forming a cutout, a locator element adapted to be received in said cutout and to project beyond a surface of said holding member, and means for adjusting the position of said locator relative to an independently fixed point.

20. 11. A feed-strip aligning means for ammunition belt-link dies comprising, a holding member including means forming a cutout extending from one of its surfaces to a generally opposite surface, said cutout being enlarged adjacent said first surface, a locator element received in said cutout and projecting beyond the said second surface of said holding member, the fit of said locator element in said cutout being loose in at

25. least one direction, an arcuate surface on the extended end portion of said locator, a head on said locator loosely receivable in the said enlarged portion of the cutout, and means for adjustably fixing the position of said locator in said cutout.

30. 12. In combination, a die for use in the manufacture of ammunition belt links, a second die adapted to cooperate with said first die, a holding member including means forming a cutout extending from one of its surfaces to a generally opposite surface, said cutout being enlarged adjacent said first surface, a locator element received in said cutout and projecting beyond said second surface of said holding member, the fit

35. of said locator element in said cutout being loose in at least one direction, a head on said locator loosely receivable in said enlarged portion of said cutout, means for adjustably fixing the position of said locator in said cutout, means for attaching

40. said holding member to said first die in a position such that said enlarged portion of said cutout faces said die, and means providing an opening on said second die adapted to at times receive the extended end of said locator element.

45. 13. In combination, a die for use in the manufacture of ammunition belt links, a second die adapted to cooperate with said first die, a holding member attached to said first die, a locator element projecting from said holding member, and means providing an opening on said second die adapted to at times receive the extended end of said locator element.

50. 14. In combination, a die for use in the manufacture of ammunition belt links, a second die adapted to cooperate with said first die, a holding member mounted upon said first die, a locator element movably mounted upon said holding member and including a portion projecting therefrom, means for adjustably fixing the position of said locator element, and means providing an opening on said second die adapted to at times receive said projecting portion of said locator element.

55. 15. In combination, a die for use in the manufacture of ammunition belt links, a second die

70. 75.

adapted to cooperate with said first die, a holding member mounted upon said first die, a locator element mounted upon said holding member and including a portion projecting therefrom, means for adjusting the position of said locator element with reference to an independently fixed point, and means providing an opening on said second die adapted to at times receive said projecting portion of said locator element.

16. In combination, a die for use in the manufacture of ammunition belt links, a second die adapted to cooperate with said first die, a locator element, means mounting said locator upon said first die and with a portion thereof projecting from said first die, means for adjusting the position of said locator with reference to said first die, and means providing an opening on said second die adapted to at times receive said projecting portion of said locator.

17. In combination, first and second dies cooperable with each other and arranged to receive therebetween a sheet metal strip for the formation of ammunition belt links, said strip having an opening therein, a holding member including means forming a cutout extending from one of its surfaces to a generally opposite surface, said cutout being enlarged adjacent said first surface, a locator element adapted to be received in said cutout and including a portion projecting beyond the said second surface of said holding member, the fit of said locator element in said cutout being loose in at least one direction, an arcuate surface on the projecting portion of said locator element, a head on said locator adapted to be loosely received in the said enlarged portion of the cutout, means for adjustably fixing the position of said locator in said cutout, means for attaching said holding member to said first die in a position such that said enlarged portion of said cutout faces said die, and means providing an opening in said second die positionable in general registry with the opening in said strip and adapted to receive said projecting portion of said locator element, whereby as said dies are brought together said locator element is guided into the opening in said strip by means of said arcuate surface and effects any required adjustment in the position of said strip with respect to said dies.

18. In combination, first and second dies cooperable with each other and arranged to receive therebetween a sheet metal strip for the formation of ammunition belt links, said sheet metal strip including means forming an opening therein, a holding member mounted upon said first die,

5 a locator element mounted upon said holding member and including a portion projecting therefrom, and means providing an opening on said second die positionable in general registry with the opening in said strip and adapted to receive said projecting portion of said locator element, whereby as said dies are brought together at least a part of said locator element passes through the opening in said strip and effects any required adjustment in the position of said strip by reason of the engagement of said locator element with at least a portion of said strip which bounds said opening.

10 19. In combination, first and second dies cooperable with each other and arranged to receive therebetween a sheet metal strip for the formation of ammunition belt links, said strip including means forming an opening therein, a holding member mounted upon said first die, a locator element mounted upon said holding member and including a portion projecting therefrom, means for adjusting the position of said locator element with reference to said dies, and means providing an opening on said second die disposed in general registry with the opening in said strip and adapted to receive said projecting portion of said locator element, whereby as said dies are brought together at least a part of said locator element passes through the opening in said strip and effects any required adjustment in the position of said strip by reason of its engagement with at least a portion of said strip which bounds said opening.

20. In combination, first and second dies cooperable with each other and arranged to receive therebetween a sheet metal strip for the formation of ammunition belt links, said strip including means forming an opening therein, a holding member mounted upon said first die, a locator element movably mounted upon said holding member and including a portion projecting therefrom, means for adjustably fixing the position of said locator element, and means providing an opening on said second die disposed in general registry with the opening in said sheet metal strip and adapted to receive said projecting portion of said locator element, whereby as said dies are brought together, at least a part of said locator element passes through the opening in said sheet metal strip making any required adjustment in the position of said strip by reason of its engagement with at least a portion of said strip which bounds said opening.

WALTER SORENSEN.
